(57) CLAIM

The ornamental design for a vehicle left front fender, as shown and described.

DESCRIPTION

FIG. 1 is a perspective view of a left front fender in accordance with an embodiment of the present invention;
FIG. 2 is a side view of the left front fender shown in FIG.

FIG. 3 is the other side view of the left front fender shown in FIG. 1;

FIG. 4 is a front view of the left front fender shown in FIG.
1; and,

FIG. 5 is a top view of the left front fender shown in FIG.

The bottom and rear views of the left front fender are not part of the claimed design. The broken lines illustrate the environment of the design and are not part of the claimed design.

1 Claim, 2 Drawing Sheets
